(57) **CLAIM**

The ornamental design for a spray gun as shown and described.

DESCRIPTION

FIG. 1 is a first perspective view of a spray gun showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged perspective view of the area encircled in FIG. 2.

The dashed broken lines on the spray gun in FIGS. 1-9 illustrate portions of the spray gun that form no part of the claimed design. The long dash short dash broken line indicates cutoff boundaries for enlarged detailed portion views and form no part of the claim.
